Primary Examiner — R. Johnson(74) *Attorney, Agent, or Firm* — Heslin Rothenberg Farley and Mesiti PC(57) **CLAIM**

The ornamental design for a seat, as shown and described.

DESCRIPTION

FIG. 1 is a perspective view of a seat, showing the first embodiment of the new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top view thereof; and,

FIG. 7 is a perspective of the seat, showing the second embodiment of the design; the portions of which are broken away to illustrate indeterminate width, which is the sole difference between it and FIGS. 1-6.

The broken lines illustrate the portions of the seat, which form no part of the claimed design. The broken breakaway lines in FIG. 7 indicate a symbolic break in the width of the design indicating no specific width. The appearance of any portion of the article between the break lines form no part of the claimed design.
